LADY'S DICKEY

Samuel Sampson, New York, N. Y.

Application July 22, 1948, Serial No. 147,707

Term of patent 7 years

(Cl. D3—25)

To all whom it may concern:

Be it known that I, Samuel Sampson, a citizen of the United States, and residing at New York, in the county of New York and State of New York, have invented a new, original, and ornamental Design for a Lady's Dickey, of which the following is a specification; reference being had to the accompanying drawing, forming part thereof, and in which

Fig. 1 is a front perspective view of a lady's dickey showing my new design, and

Fig. 2 is a plan view thereof.

I claim:

The ornamental design for a lady's dickey, substantially as shown.

SAMUEL SAMPSON.
